UNITED STATES PATENT OFFICE.

MARK D. MEEK, OF EAU CLAIRE, WISCONSIN.

STUMPING-MACHINE.

1,001,292.

Specification of Letters Patent. Patented Aug. 22, 1911.

Application filed September 22, 1910. Serial No. 583,256.

To all whom it may concern:

Be it known that I, MARK D. MEEK, citizen of the United States, residing at Eau Claire, in the county of Eau Claire and State of Wisconsin, have invented certain new and useful Improvements in Stumping-Machines, of which the following is a specification.

This invention comprehends certain new and useful improvements in logging, yarding and hoisting engines, and relates particularly to an improved machine of this character designed for use in clearing land, although it is applicable for other uses generally as above indicated.

The invention has for its primary object a simple, strong and durable machine of this type which will be efficient in operation and capable of being easily controlled, and the invention consists in certain constructions, arrangements and combinations of the parts that I shall hereinafter fully describe and claim.

For a full understanding of the invention, reference is to be had to the following description and accompanying drawings in which:

Figure 1 is a top plan view of a machine constructed in accordance with my invention; Fig. 2 is a side elevation thereof; Fig. 3 is an enlarged detail sectional view of one of the clutches employed; Fig. 4 is a side elevation looking from the side opposite to that illustrated in Fig. 2. Fig. 5 is a detail view of one part of the clutch illustrated partly in Fig. 3; and, Fig. 6 is a transverse detail sectional view through one of the other clutches.

Corresponding and like parts are referred to in the following description and indicated in all the views of the accompanying drawings by the same reference characters.

The framework of my improved machine may be of any desired construction, size, and design so long as it subserves its primary function of a strong and durable support for the operating parts and it is designed also to support a prime mover which in the present instance, is conveniently illustrated as a steam engine embodying a boiler 1, two cylinders 2 arranged on opposite sides of the boiler, steam chests 3 for the respective cylinders, pitmen 4 in the respective cylinders and valve stems 5 working in the respective steam chests. The pitmen 4 are connected by wrist pins to crank disks 6

secured to the opposite ends of a laterally extending main driving shaft 7 which is journaled in pillow blocks or other bearings in the main, side and intermediate sills of the framework. The valve stems 5 are operatively connected in any desired way to eccentrics secured to the shaft 7.

There are two loose gear wheels on the shaft 7, one designated 8 is larger than the other wheel, designated 9. The wheel 8 meshes with a relatively small pinion 10 and the gear wheel 9 meshes with a relatively large gear wheel 11. The pinion 10 and wheel 11 are both fast on a transversely extending counter shaft 12 journaled in the framework as best illustrated in Fig. 1. A winding drum 13 is also mounted on the countershaft 12 being loose thereon and is designed to be engaged with the gear wheel 11 by any desired clutch, such as that indicated at 14 in Fig. 6, and part of which is also shown in Fig. 1. The drum 13 is moved into engagement with its driving gear wheel 11 by means of a steam actuated piston rod 15, but as the specific construction of the clutch for the drums and actuating mechanism therefor form no part of my present invention, I have deemed it unnecessary to describe such parts in full. Meshing with the pinion 10 is a gear wheel 16 secured fast on another actuating shaft 17 journaled in the framework, and a pinion 18 is also secured fast on said shaft, said pinion meshing with a relatively large gear wheel 19 fast on another counter shaft 20 journaled in the framework. On this last named shaft, there are two drums, one of which is designated 21 and the other 22, each of these drums being loose on the shaft. The drum 21 is coupled to the shaft 20 through a clutch coming against or into the gear wheel 19, the clutch being operated by a piston rod 23, and the drum 22 is connected to the shaft 20 by an actuating piston rod 24 which moves the drum, or the clutch 25 thereof into engagement with a clutch member 26 fast on said shaft. It will of course be understood that all of these clutches are operated by steam pressure working against opposite faces of the pistons (not shown) in the steam cylinders 27, the steam being supplied to the cylinders in any desired way.

As above stated, both of the gear wheels 8 and 9 are mounted free or loose on the shaft 7. They are designed to be alternately coupled to the shaft and for this

purpose I have devised a clutch mechanism best illustrated in Figs. 1, 3 and 5. A clutch member 8^a is connected by bolts or similar fastening devices to the gear wheel 8, and 5 a similar clutch member 9^a is bolted or otherwise secured to the gear wheel 9. Each of these clutch members is formed with a beveled annular face as best illustrated in Fig. 3, each of said faces being designed for 10 frictional engagement by a clutch spool, said clutch spools being designated 28 and 29 respectively. The clutch spools 28 and 29 are splined on the shaft 7 as shown. In order to shift the clutch spools 28 and 29 I 15 have provided a collar 31 which is provided with a screw-threaded portion 32 and with a nut 34 designed for engagement by a rack 35 formed on one end of the piston rod 36. (See Fig. 5.) The rod or stem 36 passes 20 into a steam cylinder 37 and is secured to a piston rod 38 working in said cylinder. It will thus be understood that by moving the piston 38 in one direction or the other, the rack 35 will cause the collar 31 to turn 25 and the screw-threaded engagement of said collar with the bearing 33 will effect a longitudinal movement of the collar along the shaft and force one of the clutch spools into engagement with its complementary clutch member and permit the spring of the other 30 clutch spool to force the latter out of engagement with its clutch member. Steam may be admitted into the cylinder 37 so as to move the piston 38 in one direction or the 35 other, by means of ports 39.

Merely as an example of one use to which my improved machine may be put, let it be assumed that it is to be used in clearing land of stumps. In this use, the drum 21 40 is the main drum of the apparatus and the drum 13 is the cable feeding drum. That is to say, in the practical operation of the device, a feeding out cable will be wound around the drum 13 and secured to the hauling-in cable which is wound around the drum 21. To carry out the hauling-in cable, the feeding-out cable will be drawn out from the drum 13 by a team or by hand, and passed around a pulley supported on a 45 tree or stake driven in the ground or some other stationary object and the clutch mechanism on the shaft 7 will then be manipulated, so as to effect the operation of the drum 13 in a direction to wind up the cable on said drum and permit the hauling-in cable to pay out from the drum 21. After the cable has been paid out from the drum 21, it is connected in any desired way to the 50 stump to be pulled, and to secure the necessary power the relatively small gear 9 is at that time thrown in, so as to transmit the motion through gear wheel 11, shaft 12, gear wheels 14, 16, 18 and 19 to the drum 21. As soon as the stump has been pulled, gear 55 wheel 9 is released, and the gear wheel 8

is used. Hence, the stump will be dragged in toward the pile and from the point where it is pulled at a rapid rate and by traveling at a rapid rate will have a tendency to shake the dirt off. For close work, that is, when the stumps are close to the machine, or when they are hooking on the stumps in the paying out line, using drum 13, the gear 9 will be engaged. Then when the outer stumps, 75 from three hundred to fifteen hundred feet are gone after, the gear 8 would be engaged while using the drum 13. After the stump has been drawn into the machine, it may be hoisted and deposited upon the pile by utilizing the drum 22 and a cable arranged to wind thereon. In this operation, it is manifest that a boom will be necessary, but as the same forms no part of my present invention, I have omitted any illustration or 80 description thereof.

It is to be particularly noted that in my invention, the drums are so arranged that they turn over in the same direction, provision being had for varying the speeds, 90 without changing the direction of rotation. It will also be seen that this object is accomplished by a construction which is very simple, and by a machine which is composed of comparatively few parts that may 95 be easily manufactured and assembled, and that will be durable and not liable to get out of order.

Having thus described the invention, what is claimed as new is:—

1. A stumping machine, comprising a framework, a driving shaft journaled in said framework, gear wheels of different diameters loosely mounted on the driving shaft means for coupling said gear wheels to the driving shaft, alternately, a counter shaft, two gear wheels mounted on the counter shaft and meshing with the first named gear wheels respectively, a drum loosely mounted on the counter shaft, means for coupling the drum to the counter shaft, another counter shaft, two gear wheels mounted on the last named shaft, one of said gear wheels meshing with one of the gear wheels on the first named shaft, a third 105 countershaft, a gear wheel fast on said counter shaft meshing with the other of said gear wheels on the second named counter shaft, a drum loosely mounted on the third countershaft, and means for connecting such 110 counter shaft to said drum.

2. A stumping machine, comprising a framework, a driving shaft journaled in said framework, gear wheels of different diameters loosely mounted on the driving 115 shaft means for coupling said gear wheels to the driving shaft, alternately, a counter shaft, two gear wheels mounted on the counter shaft and meshing with the first named gear wheels respectively, a drum 120 loosely mounted on the counter shaft, means

for coupling the drum to the counter shaft, another counter shaft, two gear wheels mounted on the last named counter shaft, one of said gear wheels meshing with one of the gear wheels on the first named shaft, a third countershaft, a gear wheel fast on said counter shaft meshing with the other of said gear wheels on the second named counter shaft, drums mounted on said coun-

ter shaft, and means for separately coupling the last named drums to the third named counter shaft.

In testimony whereof I affix my signature in presence of two witnesses.

MARK D. MEEK. [L. s.]
